COMBINATION FISH RULER, SCALER, AND COMPASS

Patrick Garelli and St. Barth Alaska, both of 3812 S.
Scoville Ave., Berwyn, Ill. 60402

Filed Dec. 3, 1969, Ser. No. 20,342

Term of patent 14 years

Int. Cl. D7—06; D10—08; D22—08; D8—02
U.S. Cl. D22—31

FIG. 1 is an elevational view of our combination fish ruler, scaler, and compass, showing our new design;

FIG. 2 is a side view thereof; and

FIG. 3 is an elevational view of the side opposite that shown in FIG. 1.

We claim:

The ornamental design for a combination fish ruler, scaler, and compass, as shown.
